UNITED STATES PATENT OFFICE.

ALFRED MARCH, OF NEW BRUNSWICK, NEW JERSEY.

KNITTING-MACHINE.

SPECIFICATION forming part of Letters Patent No. 654,469, dated July 24, 1900.

Application filed September 7, 1899. Serial No. 729,756. (No model.)

To all whom it may concern:

Be it known that I, ALFRED MARCH, a citizen of the United States, residing at New Brunswick, in the county of Middlesex and 5 State of New Jersey, have invented new and useful Improvements in Knitting-Machines, of which the following is a specification.

This invention consists in certain novel details of construction set forth in the following 10 specification and claims and illustrated in the annexed drawings, in which—

Figure 1 is a rear elevation of a knitting-machine embodying this invention. Fig. 2 is a side elevation of Fig. 1, part of the carriage 15 being sectioned away. Fig. 3 is a plan view of the machine on a larger scale than in Fig. 1. Fig. 4 is a section along *v v*, Fig. 1. Fig. 5 is a section along *w w*, Fig. 1. Fig. 6 shows the pattern-chain with its actuating mechanism. Fig. 7 is a section along *x x*, Fig. 6. Fig. 8 is a sectional side elevation of the carriage and needle-bed. Fig. 9 is an inverted plan view of a cam of a carriage. Fig. 10 shows the shifter for the yarn-carrier. Fig. 11 25 shows the shifter for a tumbler-actuating lever. Fig. 12 shows the shifter for the stop-motion. Fig. 13 shows the lever for loosening meshes.

The frame or support of the machine is 30 shown at 1, and a pulley-shaft 2, Fig. 1, has the fast and loose pulleys 3 and hand or fly wheel 4. A belt 5 can be shifted by shifter 6, which latter can be actuated by hand-lever 7, Figs. 3 and 4, or by a stop-motion hereinafter 35 referred to. The shaft 2 is connected by gears 8 and 9, Fig. 1, with driving-shaft 10, which by means of miter-gears 11, Fig. 3, rotates shaft 12 with crank-arm 14, Fig. 1. Arm 14 is connected by link 15 to lever 16, 40 having fulcrum 17 conveniently secured, say, to the floor of the factory. The oscillations of lever 16 caused by rotation of arm 14 are transmitted by link 18 to carriage 19, reciprocating across needle-bed 20. The bed 20 45 is really composed of two beds or sections arranged in roof or gable shape, and the carriage 19 is frame-shaped, its two longitudinal branches corresponding to the sections of bed 20. Said carriage is caused to actuate the 50 needles in the beds by cam arrangements, one of which is shown in Fig. 9. The cam-pieces 21, 21^a, and 21^b are secured to the under side

of carriage 19 and leave between them a channel or V-shaped way to reciprocate the needles, these pieces acting as advancing and 55 retracting cams.

The needles 22, Fig. 8, have butts 23, extended through slots, and the needle-tails spring with such friction against the slots that when a needle has been raised or moved 60 up on its bed to project across the center line of the machine or the apex of bed 20, say, to the positions shown by the dotted-line needles in Fig. 8, such needle will not slip down or fall back by its weight, but has to be forced 65 back. The bed 20 has keepers or stops 24, and when the butt 23 of a needle rests against stop 24 such butt is out of the way or reach of carriage 19 or cam 21, so that the latter cannot move the needle. If, however, the 70 butt 23 is raised or moved from stop 24 a sufficient distance to come in the path of cam 21, such cam when carried by the carriage against butt 23 will by one or the other of its incline faces slide butt 23 toward the median 75 line of the machine until the apex of cam 21 has passed such butt, after which cam 21^a or 21^b moves the butt 23 away from such median line. The reciprocations of carriage 19 thus cause the needles of the opposite sets to oscillate toward and from one another so as to 80 knit. The needles can be moved from stop 24 to within reach of cam 21 by lifters secured to the carriage or mounted on the side of the carriage facing the needles. Each lifter consists of an arm 25, Fig. 9, whose hub 26 is mounted on a pivot 27, set at an angle or incline to the longitudinal diameter of the carriage, so that the lifters swing somewhat transversely to the travel of the carriage. The 85 arm 25 has its swing limited by the stops 28 and 29, and a brake or spring 30 prevents the arm accidentally moving away from the stop against which it may be resting at the time. Four such lifters are used in the construction 90 shown, one at or near each end of the base of cam or triangle 21. Each lifter 25 is moved to needle-engaging position by its lever or tumbler 31, Fig. 9. The swing of the tumbler in one direction is limited by a spring or 95 stop 32. When swinging away from this arm or stop 32, the tumbler strikes lifter 25 and carries it to stop 29, where the movements of both tumbler and lifter are stopped. The 100

2

swings of the tumbler and of the lifter are thus both limited, one by stops 28 and 29 and the other by stops 32 and 29. When a lifter rests at stop 28, such lifter cannot touch or engage 5 a butt 23 resting at butt-stop 24. When, however, the lifter is swung out or to stop 29, such lifter, as seen at the left-hand side in Fig. 8, will contact with a butt 23, the contacting face or part of the lifter being somewhat recessed or concaved to slightly lock itself to the needle-butt. Say the upper lifter in Fig. 9 has thus engaged a needle-butt and the carriage is moving in the direction of the arrow there shown. The pressure of lifter 15 25 against such needle-butt will swing or force lifter 25 from stop 29 to stop 28; but since the lifter and needle-butt are interlocked, as just stated, the butt 23, as indicated at the right hand in Fig. 8, will be carried from the position shown at stop 24 by broken lines toward the cam 21 or stop 28, as indicated in Fig. 8 at the right by full lines. By the time the lifter comes to stop 28 it has swung up far enough to clear or lie over the butt 23; but 25 such butt now lies in the path of cam 21 or within its base-line or the line extending between stops 29. When this cam is now being carried back and forth by the reciprocating carriage 19, such cam strikes butt 23 of a 30 needle and by aid of cams 21^a and 21^b will give a reciprocating or knitting stroke to such needle. On the lifter being now swung back from stop 28 to stop 29 such lifter is in position to slide or move another needle-butt into 35 the field of cam 21, and by thus moving one needle after the other into work the fabric or goods can be widened. Taking for example the series of goods or work 33, (represented in Fig. 1,) which is a series of sleeve halves or 40 sections, the narrowest part of the work, say, is the wrist or forearm part of the work, the part of intermediate width is the arm part, and the widest part the shoulder part. To knit the wrist or narrowest part, a certain number 45 of needles are at work. As the intermediate width is to be knit, each of the four lifters 25 is brought into action, so that for each back and forth travel of the carriage 19 two needles are added to the number of working needles. This addition of needles is kept up until sufficient needles are at work to knit 50 the intermediate width. As the widest part is to be knit, the lifters are again made to add to the working needles, and after the widest part is finished the machine is stopped to allow enough needles to be moved back out of action or to stop 24 to recommence the knitting of a narrowest part. This moving of needles out of action can be done by hand.

60 The tumblers 31 are operated or swung against lifters 25 by fingers 34, Fig. 8, which, as there seen by full lines, are normally out of action or out of reach of tumblers 31. These fingers project from rock-shafts 36, 65 suitably mounted, as on brackets 37, secured to suitable fixed cross-pieces—say to the needle-bed 20 of the machine. Springs 35 can

be made to normally hold the fingers out of action. When these fingers are swung inward or to the position shown by dotted lines 70 in Fig. 8, the outer arms of the tumblers 31 as carriage 19 reciprocates come against fingers 34, so that such tumblers swing to strike or move their respective lifters 25.

The rock-shafts 36 have arms 38, Fig. 5, and the lugs or projection 39, Figs. 1 and 11, when made to depress or swing arm 38 will cause shaft 36 to rock and swing fingers 34 into action. The fork 40 is shown in broken lines in Fig. 3 and is connected to lever 41, Figs. 80 1 and 11, normally held by spring 42 to keep the faces 39 away from arms 38. The lever 41 has a roller 43, against which runs pattern-chain 44, and as a raised face of this chain strikes or lifts roller 43 the lever 41 moves 85 or pushes fork 40 and projections 39 to the arms 38. The pattern-chain travels, as indicated by arrow in Fig. 1, and the pattern-chain there shown is adapted for knitting the three-width fabric shown at 33. The chain 90 has the pattern-faces 45^a to 45^b and the second set of faces 45^c to 45^d. As the part of the chain immediately preceding the face 45^a travels under roller 43 the lever 41 remains at rest and sufficient needles are kept at work to 95 form the narrowest part of the fabric. As the chain carries the faces 45^a to 45^b past roller 43 the number of working needles is increased, and while the chain carries the part or plain portion between 45^b and 45^c past roller 43 the 100 intermediate width is formed. The faces 45^c to 45^d then come into action and the fabric 33 is widened to its widest extent, after which face 46 engages the stop-motion and the machine 105 stops. Of course the invention is not confined to this specific pattern-chain, as the chain varies according to the pattern desired. The chain shown is merely an example showing one kind of chain for a certain length or kind of sleeve.

110 The stop-face 46, as seen in Fig. 12, is made to strike or move a lever 47, which, if seen fit, could have a friction-roller to ease the movement of such face. When the face 46 comes into action, lever 47 is moved against the action of spring 48 and moves link 49, as shown by the arrow in Fig. 4. This link moves lever 50 to carry the slide 51 out of engagement with catch 52, whereupon spring 53 moves this slide with belt-shifter 6 to carry 120 belt 5 off the fast pulley. The machine is not limited to any special stop-motion.

115 The chain is moved or fed about by barrel or sprocket-wheel 54, Fig. 1, whose shaft 55 has a ratchet 56, Fig. 6, engaged by pawl 125 57 on lever 58. This lever is moved in one direction by spring 59, Fig. 5, and in the other by cam 60 on shaft 10, said cam lifting link 61, which by link 62, Fig. 1, connects with lever 58. The pawl 57 in the example shown 130 is made to move the chain or the ratchet 56 only at every other stroke. An idler-ratchet 63, Fig. 3, has alternate high and low teeth, and when pawl 57 rests on a high idler-tooth

such pawl is held clear of ratchet 56 and moves only the idler-ratchet. When on its next stroke pawl 57 falls into a deep idler-tooth, it also reaches or takes hold of a tooth of the 5 chain-driving ratchet to move the latter and feed the chain. The feed of the chain is not limited to the method shown.

In the drawings are shown two yarns or threads 64, each with its carrier or thread-guide 65. When one guide travels or reciprocates across the machine, the other guide is at rest. Each guide is mounted on its track or rail 66, (shown in section in Fig. 8,) the guides 65 being mounted on what are known 10 as the "carrier-boxes" 111. The guides are secured to the boxes by screws or other suitable means. These rails 66 are carried by arms 67, pivoted at 68, one of the arms having a branch 67', Fig. 5. A tooth or cam 69, 15 Figs. 1 and 10, is formed on or screwed to a link 70, connected to lever 71. The spring 72 normally holds the lever back to keep cam 69 away from arm 67'. When the chain 44 carries a face 74 against roller 73 of lever 71 20 to cause the latter to bring tooth 69 to arm 67', the arm 67 is tilted. The carrier-actuator 75, Fig. 1, extends from and reciprocates with carriage 19, and as the arms 67, with rails 66, are tilted away from or toward the actuator 75 one guide 65 is carried out of reach of 25 the actuator and the other guide is brought into such reach or engagement. The actuator 75 thus moves but one guide at a time. The shifting of one yarn or another into or 30 out of action can be made to produce certain effects—as, for example, by having the two yarns 64 of different color or appearance. The yarns on their way to carrier-bars 65 pass through tensions 76 and guide-eyes 77.

40 The actuator 75, carried by carriage 19, reciprocates across the machine along a fixed line or path. The arms 67 as they are tilted or oscillated back or forth to and from said path, or rather across the same, bring one carrier 45 65 or the other into reach of this actuator.

The completed work 33, as seen by broken lines in Fig. 2, passes or feeds down and about a roller 78 on lever 79, fulcrumed at 80. From roller 78 the work passes about roller 50 81 and between this roller and roller 82 to the take-up axle 83, driven by belt 84, passing about shaft 10, Fig. 1. The roller 82 is driven by ratchet 86 and pawl 87, Figs. 2 and 5. The pawl is driven by lever 88, moved in one 55 direction by spring 89, Figs. 1 and 5, and in the opposite direction by cam or eccentric 90 on shaft 10. The lever 79 connects by link 91, Figs. 2 and 5, with pawl 87, and when the work passing about roller 78 is under excessive tension the lever 79 is raised or held up by the work and by the aid of link 91 and spring 92 holds the pawl 87 out of action or lifted clear of ratchet 86. As the machine continues working the pawl 87 reciprocates 60 idly and the rollers 81 and 82 remain at rest,

so that the work is not fed until the work added at the machine has slackened that part of the work about roller 78 sufficiently to allow lever 79 to drop and pawl 87 to pass back into action.

The take-up rod 83 is smooth or has no firm grip on the work rolled about the same, so that unless aided by the feed-rollers 81 and 82 the take-up 83 slips about in the work without feeding or taking up the same. If 75 desired, the take-up 83 could be left out of use and the work received in a basket or led off, as seen fit.

The pattern-chain, it is noticed, performs several functions, since it brings lifters into 80 action, and also shifts the yarn-guides 65 and actuates the stop-motion. It also in the example shown is made to automatically effect a series of loose stitches or meshes, as presently explained.

The lifter and tumbler or the pivots carrying these parts are shown mounted in or on a carrying piece or bracket 93, Fig. 8, which being a piece separate from the carriage can be made removable, adjustable, or exchangeable and set at an angle to make lifter 25 swing transversely to the carriage.

The cam-pieces 21, 21^a, and 21^b, as seen in Fig. 9, are secured to the carriage by slot and screw connections, so that the pieces can be 95 set to proper relative position before being clamped or screwed fast. The cam-pieces 21^a and 21^b, Fig. 9, have each a slot 94 engaged by an eccentric-pin 95 on a disk 96. One of these disks 96 has its stem or axle 97, Figs. 3 100 and 8, provided with an arm 98, engaged by a fork 99 on slide 100, mounted on carriage 19. When the slide is moved to turn arm 98 with pin 95, the corresponding cam-piece—say 21^a—is moved across the carriage. By bringing the 105 apex portion of cam 21^a nearer to or farther from the base of the cam 21, the carriage reciprocating back and forth, the needle-butts will be moved a greater or less extent. By 110 sufficiently increasing the throw of the needles a so-called "slack" course of loose stitches is obtained.

The slide 100 can be moved by arms or tappets 101, Figs. 3 and 8, rising from or secured to rock-shaft 102, Fig. 1. A spring 103, Fig. 115 8, tends to normally hold the arms 101 in the path of slide 100. A pusher 104, Fig. 3, tends to hold back the arms 101 out of the way of slide 100; but when the cut or recess 105 of the pusher comes to arm 101 the spring 103 120 can throw the tappets 101 into action. The pusher 104 is connected to lever 106, Fig. 13, and when this lever is moved against the action of spring 107 by the face 108 on chain 44 the pusher 104 is moved to carry the cut 105 125 to the arms 101. Of course the particular cam, as 21^a, which is to be moved by arm 98 is clamped or secured in place with sufficient friction to not move accidentally, but not so tight as not to be movable by said arm. 130

Since one chain 44 can be utilized to accomplish a number of results, as just explained, simplicity in construction is obtained.

In operation it has been found practical to proceed as follows for the particular goods shown: The narrowest part of the goods having been knit while the chain part just preceding face 45^a travels about barrel 54 said faces 45^a to 45^b add to the operating-needles to widen the fabric to intermediate width. This intermediate width is then formed while the chain part from 45^b to 45^c travels about the barrel. The faces 45^c to 45^d then add to the working needles until the widest part of the work is attained, and face 46 produces a slack course and face 108 then stops the machine. Faces 46 and 108 can both be made to stop the machine, the machine being started after stoppage by face 46, to be again stopped by face 108. The number of working needles is then reduced to again knit a narrowest portion and the machine started to form a welt in the usual way and then go on knitting a succeeding section of work. By temporarily shifting one of the cams 21 out or to the adjacent cams 21^a and 21^b, so as to have one set of needles inoperative for, say, three or four courses or strokes of the carriage, the welt is formed. This cam 21 can then be shifted back into working position. This shift of cam 21 can be done by hand, if desired. The faces 74 form stripes and the chain then goes on to face 45^a and continues as described.

As seen in Figs. 3 and 11, the faces or cams 39, which actuate the tumbler-actuating levers, are not in line with but one in advance of the other, so that these actuators 39 operate the levers 38, Fig. 5, alternately and not simultaneously.

As seen in Figs. 4 and 5, an arm 109 is pivoted at 110. As long as the work 33 is properly tightened or stretched the arm 109 is held away from the slide or shifter 51. If the work is slack or broken or comes off the needles, the arm 109, falling or pressing by its weight against slide 51, clears the latter from stop 52, so that spring 53 can shift the slide for stopping the machine.

What I claim as new, and desire to secure by Letters Patent, is—

1. A knitting-machine provided with needles and thread-guides, tracks 66 for the guides, downwardly-extended and pivoted or oscillatory arms for the tracks, an actuator located at the upper part of the guides so as not to come between the latter and the needles, a horizontal arm extended from one of the downwardly-extended arms and made to normally rest on the machine-frame, a slide made to pass under the horizontal arm for tilting the downwardly-extended arms, and a lever and chain for actuating the slide, substantially as described.

2. A knitting-machine having a carriage, pivots on the carriage, needle-lifters on the

pivots, tumbler-levers 31 made to swing freely or without spring-pressure, fingers for swinging the tumbler-levers, rock-shafts for the fingers, a fork having non-aligned projections 39 for rocking the shafts, and a chain for actuating the fork to bring first one and then the other projection to its respective rock-shaft for alternately actuating the fingers and tumblers with their lifters, substantially as described.

3. A knitting-machine having a carriage, a pivot 27 mounted obliquely in the carriage, a needle-lifter made to swing but incapable of longitudinal or sliding motion on the pivot, a holding-spring 30 for the lifter, and a tumbler 31 made in form of a first-class lever and to swing freely or without spring-pressure, said tumbler being loose or disconnected from the lifter so that one arm of the tumbler can swing to and from contact with the lifter, and the other tumbler-arm being adapted to contact with a tumbler-actuator, substantially as described.

4. A knitting-machine having a carriage, a needle-lifter pivoted or swinging on the carriage but incapable of longitudinal or sliding motion thereon, a holding-spring for the lifter, a tumbler pivoted loosely so as to swing freely or without spring-pressure on the carriage, and a tumbler-actuating finger 31, said tumbler being loose or disconnected from the lifter and from the actuating-finger, substantially as described.

5. A knitting-machine provided with a needle-bed and needles, a carriage, a lifter, a tumbler projected beyond or laterally from the lifter, a finger 34, a rock-shaft placed parallel to the needle-bed and made to swing the finger to and from reach of the tumbler, a spring for normally holding the finger away from the tumbler, and a chain for rocking the shaft to move the finger to the tumbler, substantially as described.

6. A knitting-machine having a needle-bed, needles rectilinearly movable across the bed and having butts made to align or be stopped by the bed, a carriage having lifters pivoted or swinging at an angle or incline to the needles, tumblers made to project outside the carriage, oscillating fingers 34 for actuating the tumblers, and a central cam-piece 21 and lateral cam-pieces on the carriage, and mechanism substantially as described for holding the center cam-piece so that it will not move or swing on the carriage, substantially as described.

7. A knitting-machine provided with needles, a carriage, a needle-lifter, arms 67 pivoted at their lower ends to the machine, yarn-guides at the upper ends of said arms, a stop-motion, a lever and link connection for the stop-motion, an actuator 75 made to rise from the carriage and bent over to engage the yarn-guides, and a chain made to actuate the lifter and stop-motion connection and to oscillate

the arms 67 to shift one yarn-guide or the other to the actuator, substantially as described.

8. A knitting-machine having a needle-actuating carriage provided with cam-pieces 5 made separate or independent of one another, an arm and slide 100 made to engage and shift one of the cam-pieces and being disconnected from the other cam-pieces, an actuating-arm for the slide, and a face or slide 104 for said

last-named or actuating arm, substantially as 10 described.

In testimony whereof I have hereunto set my hand in the presence of two subscribing witnesses.

ALFRED MARCH.
